(57) **CLAIM**

The ornamental design for a locker with folding seat back, as shown and described.

DESCRIPTION

FIG. 1 is a perspective view of a locker with folding seat back according to the present application.

FIG. 2 is a front view of the locker with folding seat back of FIG. 1.

FIG. 3 is a rear view of the locker with folding seat back of FIG. 1.

FIG. 4 is a right side view of the locker with folding seat back of FIG. 1.

FIG. 5 is a left side view of the locker with folding seat back of FIG. 1.

FIG. 6 is a top view of the locker with folding seat back of FIG. 1.

FIG. 7 is a bottom view of the locker with folding seat back of FIG. 1.

FIG. 8 is a perspective view of the locker with folding seat back of FIG. 1 shown with the seat back folded out according to the present application.

FIG. 9 is a perspective view of an alternative embodiment of a locker with folding seat back according to the present application.

FIG. 10 is a front view of the locker with folding seat back of FIG. 9.

FIG. 11 is a rear view of the locker with folding seat back of FIG. 9.

FIG. 12 is a right side view of the locker with folding seat back of FIG. 9.

FIG. 13 is a left side view of the locker with folding seat back of FIG. 9.

FIG. 14 is a top view of the locker with folding seat back of FIG. 9.

FIG. 15 is a bottom view of the locker with folding seat back of FIG. 9; and,

FIG. 16 is a perspective view of the locker with folding seat back of FIG. 9 shown with the seat back folded out according to the present application.

The evenly-spaced broken lines in all views are for the purpose of illustrating environmental structure, and form no part of the claimed design.

1 Claim, 13 Drawing Sheets
